(57) **CLAIM**

I claim the ornamental design for a drinking vessel, as shown and described.

DESCRIPTION

FIG. 1 is a top and side perspective view, the drinking vessel having a six-sided top section;

FIG. 2 is a side elevation view of a flat side thereof, the view of the vertex side being understood from the perspective view;

FIG. 3 is a top plan view thereof;

FIG. 4 is a bottom plan view thereof;

FIG. 5 is a vertical longitudinal sectional view along line 5—5 of FIG. 3;

FIG. 6 is a top and side perspective view of another embodiment of the drinking vessel shown in FIG. 1 having an eight-sided top section;

FIG. 7 is a side elevation view of a vertex side thereof, a view of a flat side being understood from the perspective view;

FIG. 8 is a top plan view thereof;

FIG. 9 is a bottom plan view thereof;

FIG. 10 is a vertical longitudinal sectional view taken along line 10—10 of FIG. 8;

FIG. 11 is a top and side perspective view of another embodiment of the drinking vessel showing my new design having a six-sided top section;

FIG. 12 is a side elevation view of a flat side thereof, the view of a vertex side being understood from the perspective view;

FIG. 13 is a top plan view thereof;

FIG. 14 is a bottom plan view thereof;

FIG. 15 is a vertical longitudinal sectional view along line 15—15 of FIG. 13;

FIG. 16 is a top and side perspective view of another embodiment showing of the drinking vessel shown in FIG. 1 having an eight-sided top section;

FIG. 17 is a side elevation view of a vertex side thereof, the view of a flat side being understood from the perspective view;

FIG. 18 is a top plan view thereof;

FIG. 19 is a bottom plan view thereof; and,

FIG. 20 is a vertical longitudinal sectional view along line 20—20 of FIG. 18.

The design is characterized by having relatively thin walls whose thickness may be obscured by the amount of colorant added in manufacture depending on the angle and intensity of lighting.
